UNITED STATES PATENT OFFICE.

CHARLES C. SPREEN, OF DETROIT, MICHIGAN, ASSIGNOR TO KELVINATOR CORPORATION, OF DETROIT, MICHIGAN, A CORPORATION OF DELAWARE.

COMPRESSOR.

Application filed October 17, 1923. Serial No. 669,142.

To all whom it may concern:

Be it known that I, CHARLES C. SPREEN, a citizen of the United States, residing at Detroit, in the county of Wayne and State 5 of Michigan, have invented a certain new and useful Improvement in Compressors, of which the following is a full, clear, and exact description, reference being had to the accompanying drawings.

10 It is advisable to provide, in compressors utilized for compressing the refrigerant in a mechanical refrigerating system, some means by which oil in the refrigerating system may return to the crank case of the 15 compressor. My invention provides an improved means for this purpose. In the drawings accompanying this specification and forming a part thereof I have shown, for purposes of illustration, one form 20 which my invention may assume. In these drawings the single figure represents a vertical section through a compressor embodying this illustrative form of my invention.

The compressor herein described comprises a casing 11 containing within itself a crank case chamber 12 in which is mounted a crank shaft 13 which operates, by means of a pitman 14, a piston 15 arranged to reciprocate within a cylinder 16 which 30 is receivable within the casing 11, defines within itself a compression chamber 17, defines between itself and the casing 11 an inlet chamber 18, is provided with a suitable port 19 arranged to afford communication between the inlet chamber 18 and the compression chamber 17 when the piston 15 is lowered as shown herein, and is provided with a suitable outlet valve 20 adapted to afford communication between the 40 compression chamber 17 and the outlet chamber 21.

It will be obvious from the above description that rotation of the crank shaft 13 will act through the pitman 14 to operate the piston 15 within the cylinder 16 from the position herein shown to a slightly higher position wherein the port 19 is closed and thence through a series of positions to that in which the piston 15 has 50 reached the upper limit of its travel and the fluid within the compression chamber 17 has been compressed and expelled through the outlet valve 20 into the outlet chamber 21 after which continued rotation 55 of the crank shaft 13 will retract the piston

15 into the position herein shown and by uncovering the port 19 permit the introduction of a fresh charge of refrigerant from the inlet chamber 18 into the compression chamber 17.

During the operation of the compressor oil from the crank case chamber 12 is continually splashed upon the inner walls of the cylinder 16 and, with each stroke of the piston 15, a certain amount of this oil 60 is carried into the compression chamber 13 and thus into the refrigerating system. Oil in the refrigerating system not only interferes with the proper action of the refrigerant but also causes knocking and pounding 65 of the compressor and accordingly it is highly desirable that any such oil be afforded an outlet through which it may escape from the refrigerating system. The embodiment of my invention herein disclosed provides this outlet by forming in the cylinder 16 adjacent the lower edge of the inlet chamber 18 an aperture 22 connecting the inlet chamber 18 with the crank case 12. Because of the direction in which 70 this aperture extends the likelihood of oil being splashed therethrough into the inlet chamber 18 is negligible while the suction of oil vapor into the inlet chamber 18 is prevented by closing the aperture 22, as 75 by a depending skirt 23 on the piston 15, whenever the port 19 is uncovered and fluid is being drawn from the inlet chamber 18 and by uncovering the aperture 22 only 80 when the pressure within the inlet chamber 18 is sufficient to prevent any appreciable inflow into the inlet chamber 18 through the aperture 22.

It will be apparent to those skilled in the art that I have provided an improved 85 means for permitting oil and other foreign matter to escape from the refrigerating system. At the same time, it will be readily apparent to those skilled in the art that the particular construction herein shown and 90 described may be variously modified without departing from the scope of my invention or sacrificing the advantages thereof and that this disclosure is illustrative only 95 and my invention not limited thereto.

I claim:

1. A compressor comprising a crank case chamber and an inlet chamber connected by means of a duct adapted to permit foreign matter such as oil to pass from said 100 110

inlet chamber to said crank case chamber, and comprising means arranged to maintain said duct closed whenever said inlet chamber is connected to the compression chamber of said compressor.

2. A compressor provided with a crank case chamber and an inlet chamber and a compression chamber and with a duct adapted to permit the passage from said inlet chamber to said crank case chamber of foreign matter such as oil, and comprising means arranged to maintain said duct closed whenever said inlet chamber is in communication with said compression chamber.

10 3. A compressor provided with a crank case chamber and an inlet chamber and a compression chamber and with a duct adapted to permit the passage from said inlet chamber to said crank case chamber of foreign matter such as oil, and comprising a piston cooperating with said compression chamber and adapted to close said duct during a portion of its stroke.

25 4. A compressor provided with a crank

case chamber and an inlet chamber and a compression chamber and with a duct adapted to permit the passage from said inlet chamber to said crank case chamber of foreign matter such as oil, and comprising a piston operating in said compression chamber and adapted to close said duct whenever said compression chamber is in communication with said inlet chamber.

5. A compressor provided with a crank case chamber and an inlet chamber and a compression chamber and with a duct adapted to permit the passage from said inlet chamber to said crank case chamber of foreign matter such as oil, and comprising a piston operating within said compression chamber, adapted to cover and uncover a port connecting said compression chamber with said inlet chamber, and arranged to maintain said duct closed whenever said port is open.

In testimony whereof, I hereunto affix my signature.

CHARLES C. SPREEN.
